UNITED STATES PATENT OFFICE.

CHARLES E. JOHNSON, OF NEW YORK, N. Y.

DRAWING INSTRUMENT.

1,241,986.

Specification of Letters Patent. Patented Oct. 2, 1917.

Application filed October 28, 1916. Serial No. 128,267.

To all whom it may concern:

Be it known that I, CHARLES E. JOHNSON, a citizen of the United States, residing at New York, in the county of New York and

5 State of New York, have invented new and useful Improvements in Drawing Instruments, of which the following is a specification.

The present invention relates to improvements in the construction of drafting implements.

In carrying out my invention it is my purpose to produce a drafting implement whereby curved figures of various sizes may 15 be accurately described.

It is a still further object of the invention to produce an instrument of this character which may be accurately operated by persons not particularly skilled in the art of 20 drafting, and which shall be of a simple construction, comparatively cheap to manufacture as well as efficient and accurate in operation.

With the above and other objects in view 25 the improvement resides in the construction, combination and arrangement of parts set forth in the following specification and falling within the scope of the appended claims.

In the drawings:

30 Figure 1 is a perspective view illustrating the improvement,

Fig. 2 is a central vertical longitudinal section view through the same,

Fig. 3 is a sectional view approximately 35 on the line 3—3 of Fig. 2, and

Fig. 4 is a sectional view approximately on the line 4—4 of Fig. 2.

Referring now to the drawings in detail the numeral 1 designates the foot member of 40 the instrument, the same being preferably rectangular in plan and has its underface concaved and its outer face convexed. The foot, at the corners thereof, is provided with depending entering points 2, whereby the 45 same may be effectively sustained upon the board upon which the figure is to be described. Arranged centrally upon the outer convexed surface of the foot is a sleeve 3, the same being of any desired length and 50 the same having its bore communicating with the central opening in the foot 1.

Surrounding the sleeve 3 is a body 4 having an elliptical periphery, the said body being centrally provided with an outwardly 55 extending collar 5 which, of course, also surrounds the sleeve 3, the said collar being

provided with a binding element such as a headed screw 6, whereby the body may be sustained in a longitudinally adjusted position upon the sleeve 3. While the body 4 is 60 illustrated by the drawings as of an elliptical formation, and while the instrument is primarily adapted for describing ellipses, it is here to be stated that the body 4 may be of any desired peripheral formation so that 65 the instrument may be successfully employed in describing curves of different shapes. The body 4 preferably has its underface concaved, and in order that the same may be of an equal thickness throughout the 70 outer face of the said body may be convexed as shown by the drawings.

The sleeve 3 is adapted to receive the reduced inner portion 7 of what I will term the inner leg 8 of the instrument. The portion 7 of the leg has its outer end provided with a reduced threaded extension 9 upon which is screwed a nut 10, the said nut contacting with a washer 11 which abuts against the concaved face of the foot 1 and 80 thus the leg 8 is revolvably secured to the said foot. The shoulder between the leg proper and the reduced portion 8 therefor rests upon the outer end of the sleeve 3 and the outer end of the said leg 8 terminates 85 in a head 12. This head is bifurcated or centrally slotted, a pin 13 passing transversely through the said slot, and the pin is adapted to receive the convolutions 14 of a spring member 15, one end of the said 90 spring contacting with one of the sides of the head, while the other end of the spring engages with the outer leg of the instrument, as will be hereinafter more fully apparent.

The leg 8, inward of its head 12, is formed with a transversely arranged socket 16, the said socket, adjacent one of the ends thereof, being widened and its sides provided with openings whereby to receive a revolvable member in the nature of a nut 17. The nut is peripherally rounded and its said periphery is milled and projects a suitable distance beyond the sides of the socket to permit of the turning of the said nut.

The socket 16 at the portion thereof opposite that provided with the nut and which, of course, is extended beyond the opposite side of the leg to the referred to portion provided with the nut has its underface open 110 as indicated by the numeral 18, and disposed within the socket is a headed mem-

ber 19 having a longitudinally extending shank 20. It should be stated that the bore of the socket is of a rectangular formation and that the shank 20 is of a like formation 5 in cross section, but the opposite edges of the said shank are provided with threads 21 which are engaged by the threads in the bore of the nut 17. By this arrangement it will be noted that upon the manipulation 10 of the nut 17 the head 19 may be moved laterally in either direction with respect to the leg 8.

Pivotedly secured, as at 22, to the head 19 of the adjustable shank 20 is the bifurcated end or head 23 of the outer leg 24 of the instrument, and the spring 15 contacting with the said outer leg 24 will swing the same upon the pivot 22 into contacting engagement with the periphery of the 20 body 4.

The leg 24 is provided with an opening which enters from the outer end thereof so that the shank 25 of the marking member 26 may be received therein. The leg is provided with a binding element 27, in the nature of a set screw which contacts with the shank 25 and retains the same in a properly adjusted position with respect to the leg 24. The leg 24, upon the outer face thereof, 25 and adjacent the outer or lower end of the same is provided with a longitudinally arranged slot 28, communicating with the bore of the said leg and passing through this slot and adapted to be received in one of a 30 plurality of spaced perforations in the shank 25 is the stem 29 of a headed member 30.

Disposed within the bore of the leg 24 and having one of its ends secured therein in any desired or preferred manner is a 40 helical spring 31, the opposite end of the said spring being secured to the shank 29 of the member 30, and by arranging the said shank in a desired perforation 32 in the shank 25 the pressure of the marking 45 element 26 upon the board or paper may be nicely regulated.

It is to be understood that the marking element 26 is in the nature of a removable member so that the shank 25 may be provided with either a pencilsing or an inking instrument.

It will, it is thought, be perfectly obvious to those acquainted with the employment of an instrument as herein described, that it 55 is merely necessary to adjust the guide body 4, or what may be termed the ellipsis of the instrument, longitudinally of the sleeve 3 to cause the leg 24 to be moved outwardly or inwardly with respect to the sleeve 3 and 60 foot 1, so that curved figures of different sizes may be described by revolving the leg 8 around the sleeve 3. It will also be apparent that figures of varying sizes may be described without adjusting the member 4, 65 in which instance the nut 17 is turned to

move the member 20 longitudinally of the socket 16, and this latter method of adjustment, is also desirable when the marking implement is in the nature of a pen and wherein both of the nibs of the pen are desired to be properly brought into contact with the paper or board upon which the ellipse is to be described.

The adjustable means which pivotally secures the outer leg of the compass to the inner leg thereof also permits of the device describing elliptical figures of different breadths without adjusting the form 4, as for instance, when it is desirable that the figure be of a less width than would be ordinarily described in a manner as above set forth, the nut 17 is turned to permit of the outer leg being swung inwardly to the sides of the body 4, and by such adjustment it will, it is thought, be readily apparent that 85 the breadth of the figure may be properly proportioned to suit the demands of the user.

Having thus described the invention, what I claim is:

1. In a drafting instrument, a compass including an inner and an outer leg, a body adjustably associated with the inner leg, a longitudinally adjustable element arranged transversely of the inner leg, a pivotal connection between said element and the outer leg, and spring means for swinging the outer leg into contact with the adjustable body.

2. In a drafting implement, the combination with an elliptical body, of a compass comprising an inner and an outer leg and the said inner leg revolvably associated with the said elliptical body, an adjustable member arranged transversely of the inner leg, a pivotal connection between said member and the outer leg, and spring means connected with the inner leg and engaging with the outer leg to force the latter into contacting engagement with the elliptical body.

3. In a drafting implement, the combination with an elliptical body, of a compass comprising an inner and an outer leg and said inner leg revolvably associated with the said elliptical body, a longitudinally adjustable element arranged transversely of the inner leg, a pivotal connection between said element and the outer leg, spring means for swinging the outer leg into peripheral engagement with the elliptical body, a 120 marking element associated with the outer leg, spring means for normally projecting the said marking element outward of the said outer leg, and adjustable means for regulating said spring means.

4. In a drafting implement, a foot having a sleeve projecting therefrom, an elliptical body adjustably secured to the sleeve, a compass including an inner and an outer leg, said inner leg journaled in the sleeve, a 130

laterally disposed longitudinally adjustable element associated with the inner leg, and a pivotal connection between said element and the outer leg of the compass.

5 5. In a drafting implement, a foot member having entering points and having a sleeve connected thereto, a compass including an inner and an outer leg, the inner leg of the compass journaled in the sleeve, a 10 longitudinally adjustable element associated with the inner leg and disposed transversely thereof, a pivotal connection between the said element and the outer leg of the compass, spring means upon the inner leg and 15 engaging with the outer leg for swinging the latter in the direction of the inner leg, and an adjustable body upon the sleeve disposed to contact with the said outer leg to limit the inward swinging thereof and to 20 serve as a guide for the said outer leg when the instrument is in use.

6. In a drafting instrument, a foot having its corners provided with entering points, a sleeve for the foot, a body having 25 its periphery of an elliptical formation ad-

justably arranged upon the sleeve, a compass, one of the legs of the compass journaled in the sleeve, a socket arranged transversely of the leg, a headed member having a threaded shank disposed in the socket, a 30 nut engaging said shank and arranged in a transverse opening in the socket, the second leg of the compass being pivotally secured to the head of the said member, a coiled spring upon the first mentioned leg 35 and engaging with the second mentioned leg to swing the latter against the elliptical body, said second mentioned leg having a bore, a marking element having its shank arranged within the bore, a binding element 40 upon the said leg engaging with the shank, said shank having spaced perforations, a member passing through a slot in the said second mentioned leg and received in one of the perforations, and a pressure spring 45 secured within the bore of the leg and engaging the said member.

In testimony whereof I affix my signature.

CHARLES E. JOHNSON.
